CLOTHESLINE POLE CAP

John Frank Reith, Syracuse, N. Y.

Application August 1, 1949, Serial No. 4,237

Term of patent 14 years

(Cl. D49—1)

To all whom it may concern:

Be it known that I, John Frank Reith, a citizen of the United States of America, residing at Syracuse, in the county of Onondaga and State of New York, have invented a new, original, and ornamental Design for a Clothes Line Pole Cap, of which the following is a specification, reference being had to the accompanying drawing, forming part thereof.

Figure 1 is an elevational view of a clothes line pole cap showing my new design as it appears from either side;

Figure 2 is an elevational view thereof showing my clothes line pole cap as it appears from either side at right angles to Figure 1;

Figure 3 is a top plan view thereof; and
Figure 4 is a bottom plan view thereof.

I claim:

The ornamental design for a clothes line pole cap, as shown.

JOHN FRANK REITH.
